UNITED STATES PATENT OFFICE.

JOSEPH STUBBERS, OF COVINGTON, KENTUCKY, ASSIGNOR TO THE INCANDESCENT LIGHT & STOVE COMPANY, OF CINCINNATI, OHIO, A CORPORATION OF OHIO.

HYDROCARBON-BURNER.

No. 926,300.

Specification of Letters Patent.

Patented June 29, 1909.

Application filed July 16, 1908. Serial No. 443,855.

To all whom it may concern:

Be it known that I, JOSEPH STUBBERS, a citizen of the United States, residing at Covington, in the county of Kenton and State of Kentucky, have invented certain new and useful Improvements in Hydrocarbon-Burners, of which the following is a specification.

My invention relates to an improvement in a hydrocarbon heating burner where the air and gas are already properly mixed.

The object of the invention is to provide a burner which may be used with means for simultaneously controlling the area of gas inlet to the burner, and the area of the ignition orifices, that is, the outlet from the burner.

The features of the invention are more fully set forth in the description of the accompanying drawings, forming a part of this specification, in which:

Figure 1 is a side elevation. Figs. 2 and 3 are central vertical sections showing the adjusting device in different positions.

In ordinary practice, the area of the ignition orifices remains constant, while the volume of gas admitted to the burner is controlled by valve mechanism. As this ignition orifice area is proportioned to take care of the maximum gas supply, it follows that when a lesser amount of gas is delivered to the burner, it is not sufficient in volume to properly correspond with the large area of ignition orifice, and the flame will burn close to the burner, thereby heating it very hot so that the burner will burn out and it is also liable to heat it so much that it will flashback. The liability of the flame to extinguish itself under these conditions is a familiar experience. With my device the relative areas are properly predetermined and simultaneously controlled so that the full area of the ignition orifice is only in commission when the burner is receiving its full supply of gas, and vice versa, thereby delivering the gas with an equal pressure from the ignition orifices all the time.

1 represents the gas tube, on the end of which is seated the burner 2, having the ori-

fices 3 for ignition, these orifices being shown in four different horizontal rows. The pipe 1 is provided with the longitudinal slots 4, through which the gas is admitted to the burner.

5 represents a controller having a reduced diameter portion 6 telescoping on and fitting the pipe 1, and having a larger diameter portion 7 telescoping on and fitting the burner 2. The controller 5 is preferably secured in position by means of the pin 8 passing diametrically through two of the orifices 4 of the pipe 1.

9 represents a bracket secured on pipe 1 to the upper end of which is pivoted a lever 10, provided with a yoke end engaging the pin 8 for actuating the controller 5, and having its outer end provided with a handle 12.

The upper end of controller portion 6 is preferably provided at its inner periphery with the beveled seat 14, adapted to seat against the beveled surface piston of the piece 16, upon which the burner is mounted on the pipe 1 to shut off gas from the burner, see Fig. 2. The controller portion 6 operates effectively adjacent to orifices 4 to vary the area of the gas inlet into the burner, this gas passage being indicated by the arrow, Fig. 3.

The controller portion 7 effectively operates adjacent to the ignition orifices 3 to expose more or less of the rows of orifices as the controller 5 is adjusted. When the smallest amount of gas is admitted to the burner only the top row of ignition orifices will be open, and when the full amount of gas is admitted all of the orifices will be open, or the area of ignition orifice will be always proportioned to the area of gas inlet into the burner.

Having described my invention, I claim:

1. In a device of the class described, a gas pipe and burner thereon formed with communicating orifices, the burner being formed with ignition orifices, a sleeve engaging said pipe and burner and formed with means for simultaneously covering and uncovering said orifices to control the volume of gas admitted to the burner and through the ignition orifices, substantially as described.

2. In a device of the class described, a gas pipe and burner thereon formed with communicating orifices, the burner being formed with ignition orifices, a sleeve telescopically engaging the pipe and burner and adapted to simultaneously cover and uncover the said gas orifices to control the volume of gas admitted to the burner and escaping through

the ignition orifices, substantially as described.

In testimony whereof, I have hereunto set my hand.

JOSEPH STUBBERS.
